CLAIM

The ornamental design for a clock with recessed dock, as shown and described.

DESCRIPTION

FIG. 1 is a front perspective view of a clock with recessed dock according to my new design;

FIG. 2 is a front view of the design of FIG. 1;

FIG. 3 is a rear view of the design of FIG. 1;

FIG. 4 is a left side view of the design of FIG. 1;

FIG. 5 is a right side view of the design of FIG. 1;

FIG. 6 is a top view of the design of FIG. 1;

FIG. 7 is a bottom view of the design of FIG. 1; and,

FIG. 8 is a rear view of the design of FIG. 1, now shown with a rear door removed.

The dash-dash broken lines, including the logo, the opening in the cylindrical wall, the bottom surface, the feet, and the sockets and plugs (for electrical power and data), illustrate environmental structure that form no part of the claimed design. The dot-dash broken line defines the bounds of the claimed design and form no part thereof.

Conventional contour lines are illustrated for purposes of highlighting the solid-rendering, but form no part of the claimed design.
